BURNER UNIT

Roy Johnson, Seattle, Wash.

Application May 18, 1936, Serial No. 80,335

5 Claims. (Cl. 110—101)

My invention relates to the burner unit of an overfeed type of coal stoker, and would ordinarily be associated with automatic feeding means to constitute an automatic stoker. The fuel employed will usually be coal, although my invention is not to be limited to the use of coal alone, as other materials may be burned in this unit or mingled with the coal.

Burners have generally been made of cast iron or like metal, for the reason that the cast iron resists distortion and burning out when subjected to the heat of the fire, and does not tend to cause the formation of clinkers. Cast iron construction, however, is relatively expensive in the shape necessary for such burners. It is one of the principal objects of this invention to provide a burner structure which primarily by the use of structural steel shapes and steel plate can be welded together, and can be assembled cheaply, yet effectively, and which is provided, if need be, with cast iron elements which can be very cheaply made, to be used at points where the fire would tend to burn out or cause clinkers if of steel construction, so that the whole burner may be produced less expensively and at least as quickly and conveniently as a cast burner unit.

It is a further object to incorporate in such a burner unit, as the principal element thereof and the one which gives it its principal strength, a piece of structural steel shape, such as an I-beam or channel, and to build around this the necessary fuel chamber and air chamber.

My invention comprises the novel burner unit and the novel parts thereof, and more particularly the combination of different metals and the arrangement of the several parts relatively to each other, as shown in the accompanying drawing, and as will be hereinafter described and claimed.

40 In the accompanying drawing I have shown my invention embodied in an illustrative form as now preferred by me.

Figure 1 is a plan view of the complete burner unit.

45 Figure 2 is a longitudinal section through the same, substantially on the line 2—2 of Figure 1, and

Figure 3 is a transverse section substantially on the line 3—3 of Figure 1.

50 The basis of the burner unit may well be a steel channel shape 1, consisting of a web 10 joining two upright sides 11. The web 10, forming the hearth, must be supported in position elevated somewhat above the floor to provide an air chamber beneath it, preferably by a pan or

5 box 2, formed to extend beneath the web 10 and welded thereto as indicated at 20. If desired, the upper flanges and web of an I-beam shape might constitute the flanges 11 and web 10, respectively, and the downwardly projecting flanges would 10 form a support for the fuel chamber 15 and sides for the air chamber 21. The box 2 itself may be of corner welded construction, cut from sheet steel, or, where an I-beam shape is used, the sheet 15 steel would form the bottom and ends of the box. This, in conjunction with the web 10, constitutes an air chamber 21.

The hearth is provided with slits 30 constituting grate apertures. Since it is desirable to employ a cast iron grate, coal tending to clinker and 20 stick to a steel grate, it is preferred that a large aperture 12 be cut in the web 10, and a cast grate 3, having the slits 30, be provided of a size to fit the aperture 12, and suitably supported in the aperture 12 flush with the upper surface of the 25 web 10. To this end cleats 13 may be welded to the underside of the web at two opposite edges of the aperture 12. By removing the grate 3 the air chamber 21 may be cleaned out when necessary.

25 It is desirable that the fuel be permitted to spread somewhat by the time it reaches the fire. It is delivered from a fuel supply pipe 5 by any suitable means which advances it therealong to deliver it upon the upper surface of the web 10; 30 for example a worm 50 may be employed. The pipe 5, then, is connected to the end of the burner opposite the grate 3, and to form a fuel chamber 15 for the spread of the fuel and to confine 35 gases distilled from the coal and to force them through the burning mass, I preferably provide a hood 14 of inverted U-shape form in cross section, which may be made from a structural channel shape, resting upon and welded at 19 to the upper edges of the flanges 11, and extending inward to a point adjacent the grate 3. The fuel chamber 15 is completed by an end plate 16 which is welded across the end of the channel 1 and of the hood 14, suitably apertured for the reception of the fuel pipe 5 and an air supply pipe 6. 45 Since the stoker is of the overfeed type, the opposite end of the fuel chamber 15 is left open for discharge of ashes therefrom over the edge of the web 10.

Air for combustion is supplied preferably under 50 pressure through the air supply pipe 6, which connects with the air chamber 21. This pipe, which for simplicity and cheapness should be round, is shown as of somewhat larger diameter than the height of the air chamber 21, and simi- 55

larly the fuel supply pipe 5 is somewhat greater in diameter than the height of the fuel chamber 15. In order to accommodate these pipes, which are welded in place in the end plate 16 of the burner unit, or in the end of the pan 2, the web 10 is swaged, as indicated at 17, to accommodate the fuel pipe, and at 18 to accommodate the air pipe.

The coal piles up, over the grate 3, to a level 10 somewhat adjacent the upper surface of the hood 14. It must be prevented from spilling over the edges of the flanges and upon the hood, and it is undesirable that the steel parts be subjected to the direct heat of the fire. I therefore prefer- 15 ably provide an apron 7 which surrounds or encircles the fire on at least three sides. As the gases, distilled by the heat of the fire from the fresh fuel behind the grate 3 and beneath the hood 14, emerge above the flanges 11 and over 20 the front edge of the hood 14, they are constrained by the apron 7 from escaping unburned in directions laterally outward from the top edges of the fuel and combustion chambers, but instead are directed up through the burning top 25 layer of fuel and the heated zone thereabove. Such gases are there burned, increasing the efficiency of combustion, instead of being wasted. Furthermore, the fire is rendered more effective by being directed, by the apron 7, upward as a 30 concentrated column of intensely hot flame instead of spreading outward over a greater area. This upstanding apron is of cast metal, and rests upon the upper edges of the flanges 11 inwardly of the end of the hood 14, and upon the 35 inner end of the hood itself. This piece may be renewed if damaged or burned out, as may the grate 3, and thus all parts likely to be burned out can be readily replaced.

The burner unit, except for these removable pieces 3 and 7, is formed as one integral unit, 40 all welded together and of extremely compact and sturdy construction, particularly so as it has incorporated in it a structural steel shape, such as a channel or I-beam, 1. It is readily 45 inserted through the ash door of a furnace, for example, and the apron 7 may be put in place after proper installation of the main burner unit. In manufacture the shape 1 may be cut into suitable lengths with facility, and the remaining 50 parts are of simple construction and the welding of these parts together is very easily and cheaply accomplished. As a result not only is the burner strong and sturdy and long lasting, but it is inexpensive and readily installed.

55 What I claim as my invention is:

1. A burner unit for automatic stokers comprising a length of steel channel disposed horizontally, and having a web forming a hearth, and upstanding flanges, and apertured in its web adjacent one end, a cast grate removably received in said aperture, a box welded beneath the web, constituting an air chamber communicating with the grate aperture, an air supply pipe discharging into said air chamber, a hood covering the top of the channel end remote from the grate aperture end, and welded to the longi-

tudinal flange edges, a fuel supply pipe delivering fuel upon the hearth beneath the hood for advance towards the grate, and a cast apron extending upward from the edges of the channel flanges, outside of the hood, and from the edge 5 of the hood adjacent thereto.

2. A burner unit for automatic stokers comprising a length of steel channel disposed horizontally and having a web forming a hearth, and upstanding flanges, a hood covering the top 10 of one end of said channel and welded to the longitudinal flange edges, to define a fuel chamber, the web of the uncovered channel end having grate apertures therethrough, a fuel supply pipe to deliver fuel to the covered end of the 15 fuel chamber, a box underlying and welded to the channel and constituting an air chamber communicating with the grate apertures, an air supply pipe to deliver air to the air chamber, and a cast apron of U-shape extending upward 20 from the uncovered edges of the two flanges and the adjacent edge of the hood, to retain the live coals, to confine the gases distilled from the unburned coal, and to direct the flame upward in a column.

25

3. The combination of claim 2, wherein the fuel supply pipe is of greater diameter than the height of the hood above the channel's web, and the air supply pipe is of greater diameter than the air chamber, the web being downwardly and 30 upwardly swaged, respectively, to receive said pipes.

35

4. A burner unit for automatic stokers of the overfeed type, comprising a hearth having an unobstructed edge constituting a discharge end 35 for passage of ashes thereover, its opposite end constituting a fuel feed end, side walls integral with said hearth and upstanding from opposite sides thereof, a hood covering a portion of said hearth and the adjacent portions of the side 40 walls at the feed end thereof, a grate in said hearth, outside of the hood, a fuel supply conduit to deliver fuel to the feed end of said hearth and beneath said hood, and a U-shaped apron of a size to seat upon the uncovered portions of 45 said side walls and that edge of said hood which is remote from the supply conduit, and extending upwardly well above said hood and side walls.

45

5. A burner unit for automatic stokers of the overfeed type, comprising a hearth having an unobstructed edge constituting a discharge end 50 for passage of ashes thereover, its opposite end constituting a feed end, a grate in said hearth, an air supply conduit communicating with the space beneath said grate, side walls upstanding 55 from opposite sides of said hearth, a hood covering the feed end of said hearth and the adjacent portions of the side walls and terminating short of said grate, a fuel supply conduit to deliver fuel to the feed end of said hearth and beneath 60 said hood, and a U-shaped apron of a size to seat upon the uncovered portion of said side walls and that edge of said hood which is remote from the fuel supply conduit, and extending upwardly well above said hood and side walls.
